A. J. BAKER & R. T. HAZELTON
CHIP CONFINING FRAME,
APPLICATION FILED MAR. 4, 1914.

1,096,588.

Patented May 12, 1914.

UNITED STATES PATENT OFFICE.

ARTHUR J. BAKER AND ROBERT T. HAZELTON, OF CINCINNATI, OHIO, ASSIGNEES TO
THE CINCINNATI MILLING MACHINE COMPANY, OF OAKLEY, OHIO, A CORPORA-
TION OF OHIO.

CHIP-CONFINING FRAME.

1,096,588.

Specification of Letters Patent. Patented May 12, 1914.

Application filed March 4, 1914. Serial No. 822,284.

To all whom it may concern:

Be it known that we, ARTHUR J. BAKER, subject of the King of Great Britain, and ROBERT T. HAZELTON, a citizen of the United States, both residing at Cincinnati, in the county of Hamilton and State of Ohio, have invented a new and Improved Chip-Confining Frame, of which the following specification is a full disclosure.

10. This invention relates to machine tools, and it proposes an improvement therein whereby its tooling capacity will be greatly enhanced by providing an organization having superior facilities for accommodating a much greater flow of the tool cooling medium than has heretofore been usual, and whereby the work parts of the mechanism may be kept free from chips and cuttings, notwithstanding a much greater production 20 thereof than has heretofore been issued.

One object within the contemplation of this invention is to devise a very simple instrumentality which may be used in conjunction with the table of a conventional 25 milling machine or other machine tool, and which will not only prevent an undue scattering of the chips from the tool, but which will also serve as a splash guard in confining the cooling medium and properly directing 30 its flow through appropriate channels provided by the table.

Another object is to provide an arrangement of the nature revealed, which will be essentially handy in that it may be easily 35 applied and removed without interfering with the work, and which may be used without hampering the accessibility of the operator to the pieces being machined.

Another object is to create a very simple 40 arrangement, which when used in conjunction with the table of the milling machine will confine the chips in such a manner that they may easily be removed by the operator, and which would prevent them from running into, and clogging up, or unduly constricting the channels provided by the table for the flow of the cooling medium into the return well.

Other objects will be in part rendered apparent by the accompanying drawings, and will be in part rendered obvious in connection therewith by means of the following detailed description.

In order that this invention may be disclosed so fully as to enable others skilled in

the art to apply it in the various forms best adapted for any given purpose, drawings of an illustrative embodiment thereof have been annexed as a part of this disclosure, and in such drawings like characters of reference denote corresponding parts throughout all of the views of which—

Figure 1 is a fragmentary perspective indicating the table of a milling machine with a frame embodying our invention coöperating therewith. Fig. 2 is a plan view showing our oil guard and chip confiner positioned in operative relation with a table. Fig. 3 is a sectional side elevation through line 3—3 of Fig. 2, illustrating certain details thereof. Fig. 4 is a transverse section taken through line 4—4 of Fig. 2. Fig. 5 is a perspective of the perforate L-shaped part of this frame constituting a strainer for the oil and chips.

Continuing now by way of a more detailed description, it may be noted that the means herein disclosed is of particular utility in conjunction with the means for increasing the cutter efficiency invented by A. J. Baker and disclosed and claimed in his copending application, Serial No. 812,188, filed Jan. 15, 1914. Said means forms a circulating system embodying a hood maintaining a flood of a cooling medium intimately in contact with a rotating cutter to exert a comparatively prolonged refrigerating effect on each heated tooth during its return passage to its next cutting or operating station. In consequence of the use of said means, the normal rate of tooling of a machine tool is very greatly increased; so much so that the conventional tables would be overrun by the greatly increased production of chips, and would be ordinarily inadequate to carry off the very much greater quantities of cooling medium that result from the said means. By utilizing this instrumentality, however, many conventional tables may serve in conjunction by said efficiency increasing means, and the design of new tables is also greatly simplified.

In general it may be stated that this invention preferably finds its embodiment in the combination of a machine tool table suitably grooved to enable work to be bolted thereto, and having appropriate conduits for the escape of the cooling medium, together with a detachable frame having a proper relation and coöperating effect with

the grooves of the table for the purposes mentioned. While this frame may be adapted for ordinary tables, preferably, however, such tables will be slightly modified and given a greater capacity.

Referring to the drawings, A indicates a table which will be mounted to reciprocate on the usual bed provided by the machine tool, and which provides a work supporting portion 1 having a series of parallel T-slots which are adapted to receive the heads of the bolts employed for securing the work to the portion 1, as will be understood. This work supporting portion 1 is preferably surrounded on all four sides by drainage grooves or channels adapted to carry off the cooling medium received by the table. Thus, two longitudinally extending channels 3—3, may be provided; one at the forward and the other at the rearward margin of the work supporting portion 1, or what may be called the plateau of the table. These channels, 3, are preferably especially adapted for carrying off the cooling fluid, and accordingly they may differ in contour from the bolt retaining slots 2, and be of greater capacity than the same, although they may be designed, if desired, so as also to act as bolt retaining slots. The upper outer edge 4 of these channels 3 will preferably terminate in about the same horizontal plane with the plateau 1. At the one end of the table is the end channel 5, having its bottom 6 at a relative high elevation, and leading into and continuous with the upper end 7 of the bottom 8 of the channel 3, which channel bottom preferably slopes downwardly toward a point 9 into a transverse drainage conduit 10. The end channel 5 need not be of as great a cross-sectional area or capacity as the drainage conduit 10, because the latter will receive all of the overflowing fluid and the former only a portion thereof. In like manner, the bottom 11 of the drainage conduit 10 may be positioned below the point 9, and may slope from the point 12 (Fig. 4) to the point 13 to direct the outflow of the cooling medium through the port 14. Thereafter this fluid will by suitable means, not illustrated, return to an appropriate oil well in the base of the machine, and be then pumped back to the cutter and so on in an endless cycle. The end edges of the plateau 1 preferably terminated are indicated by 15 and 16.

This invention proposes also a frame B, preferably in the form of an open rectangle, and preferably also constructed of sheet metal so that it may be made very light and at the same time durable, even when handled roughly. This frame is composed of L shaped side and end members, which are here formed of rolled iron, cut at an angle and welded together at the parting lines. Thus, the end member 17 provides

an uprising flange 18, which may extend as high as desired, and a horizontal web 19. This web is cut at each end at an angle of 45 degrees, as indicated by 20, and the resulting edges are welded to similarly formed side members 21 and 22. The chip retainer 23 has its web 24 secured to the under side of the web 19 by means of rivets 25 or otherwise, and it provides a depending shield portion 26 that may be inclined slightly as shown, and which sufficiently closes the ends of the T-shaped slots 2 to prevent the chips from flowing therefrom into the channel 5. The transverse L-shaped member 27 located at the other end of this frame, i. e., adjacent to the drainage conduit 10, is constructed similarly to the member 17, but the parts are so proportioned that instead of overlying, or falling short of the transverse drainage channel (as does the member 17) it lies mainly beyond the same to make provision for the chip screening member directly overlying the drainage channel 10. This straining member is shown in perspective by Fig. 5, and it consists of a rather extensive web portion 28 perforated with a multiplicity of holes of about 12 gage, and it also provides a flange like portion 29 for the same purpose and of the same construction as the flange 26 of the other member. This strainer is formed of some wear resisting material, such as sheet steel, and along its free margin 30 it is riveted to the free margin 31 of the member 27, and adjacent its bent edge 31 riveted to a crossbar 32, which in turn is riveted longitudinally to members 21 and 22 of the frame at such a point that the downturn flange 29 will bear against the edge 16 of the plateau, or tool supporting portion 1, and preclude the passing of chips thereto into drainage well 10. From the foregoing description it will be apparent that this arrangement in point of construction is exceedingly simple and yet effective for the purposes indicated. It does not interfere with the work bolted to the table, and it prevents the chips from passing into the escape channels without unduly obstructing the flow of the cooling fluid, and it can instantly be applied to and removed from the table, and the workman can very easily shovel out the accumulating chips without any hindrance. For the purpose of preventing oil from creeping unduly along the bottom surface of longitudinal members of this frame, and thereby, perhaps, undesirably reaching other parts of the machine, it is proposed to secure small flanges 33 to the underside of the side members 21 and 22, preferably in overlying relation with the longitudinal channel 3, as shown more fully by Fig. 4. These ribs or flanges, like the flanges 26 and 29, will deflect excess oil and cause it to drip into the underlying channels.

Having thus revealed this invention, we claim as new and desire to secure by Letters Patent of the United States:—

1. A mechanism of the nature disclosed combining a table having a work-supporting area and providing adjacent one end a depressed channel for receiving drainage from the table; an open-frame providing elevated side-guards superposed on said table to expose said work-supporting area and extending beyond said channel; and a screen-element extending across said channel to restrain chips from entering the same and to permit cooling-fluid to escape into said channel; the said guards of said frame preventing the chips from escaping said work-supporting area. 70
2. A mechanism of the nature disclosed combining a table having a work-supporting area and providing adjacent one end a depressed channel for receiving drainage from the table; an open-frame superposed on said table to expose said work-supporting area and extending beyond said channel; said frame providing side guards adapted to prevent the chips from escaping said work-supporting area; a screen-element extending across said channel to restrain chips from entering the same and to permit cooling-fluid to escape into said channel; said screen-element being secured to said frame and movable as a unit therewith. 80
3. A mechanism of the nature disclosed combining a table having adjacent one end a depressed channel for receiving drainage from the table and having a number of T-shaped slots opening into said channel; an open frame superposed on said table and providing uprising side-guards extending beyond said channel; a screen member extending across said channel to restrain chips from entering the same and to permit cooling-fluid to escape into said channel, and means for closing the ends of said T-shaped slots to prevent chips from entering said channel through said slots. 90
4. A mechanism of the nature disclosed combining a table having adjacent one end a depressed channel for receiving drainage from the table and having a number of T-shaped slots opening into said channel; an open frame providing uprising side-guards and superposed on said table; and a flange-like element secured to said frame and depending from the under-side thereof into a position obstructing the open ends of said slots to restrain chips from entering said channel through the same and to permit cooling-fluid to escape into said channel. 100
5. A mechanism of the nature disclosed combining a table having a slotted work-supporting area and providing adjacent each end thereof a depressed channel for receiving drainage from said area; an open-frame providing elevated side-guards superposed on said table to expose said work-supporting area; and a flange-like element extending into each of said channels across the open ends of said slots to restrain chips from entering the channels and to permit cooling-fluid to escape into said channel; the said guards of said frame preventing the chips from escaping said work-supporting area. 110
6. A mechanism of the nature disclosed combining a table providing a work-supporting area having adjacent each end a depressed channel for receiving drainage from the table and having a number of T-shaped slots opening at each end into said channels; and an open frame superposed on said table and providing uprising side-guards to restrain the chips to said work-supporting area; and a flange-like element extending across the open ends of the T-slots in each of said channels to restrain chips from entering the same and to permit cooling-fluid to escape into said channels. 120
7. A structure of the nature disclosed comprising an open-frame providing side and end members presenting a continuous uprising rim adapted to confine chips, and providing two flange-like portions depending from its under-side adjacent each end thereof and adapted to enter the overflow channels at the ends of the table of a machine-tool to position said frame thereon and prevent chips from entering said channels. 130
8. A structure of the nature disclosed comprising an open-frame forming a continuous uprising rim adapted to confine chips, and a screen-element secured to said open-frame near one end thereof and adapted to take position over a drainage channel of a machine-tool table to exclude chips therefrom. 100
9. A structure of the nature disclosed comprising an open-frame providing side and end members presenting a continuous uprising rim adapted to confine chips, and providing two opposite flange-like portions depending from its under-side adjacent opposite margins thereof and adapted to enter channels in the table of a machine-tool to 110 position said frame thereon. 110
10. A structure of the nature disclosed comprising an open-frame forming a continuous uprising rim adapted to confine chips, a screen-element secured to said open-frame near one end thereof and adapted to take position over a drainage channel of a machine-tool table to exclude chips therefrom, and a flange depending from the underside of said frame and extending transversely thereof. 120
11. A structure of the nature disclosed comprising an open-frame providing side and end members presenting a continuous uprising rim adapted to confine chips, and 130

providing a flange-like portion depending from its underside adjacent one end thereof and adapted to enter an overflow channel in the table of a machine-tool and assist in 5 positioning said frame thereon.

12. A structure of the nature disclosed comprising an open-frame forming a continuous uprising rim adapted to confine chips, a flat perforated screen-element secured to said open-frame in the horizontal plane thereof and near one end thereof and 10 adapted to take position over a drainage channel of a machine-tool table to exclude

chips therefrom, and a rib-like means depending from the underside of said frame 15 and adapted to prevent fluid from creeping along the underside of said frame to the outer margins thereof.

In witness whereof, we hereunto subscribe our names, as attested by the two subscribing witnesses.
